United States Patent Office

Des. 182,716
Patented May 6, 1958

182,716

WHEELED HAND CART

Ruth R. Ferguson, Atlanta, Ga.

Application June 18, 1956, Serial No. 41,939

Term of patent 14 years

(Cl. D14—3)

*Fig. 2*Fig. 1 is an upright perspective view, showing the front and one side of a wheeled hand cart showing my design.

Fig. 2 is a perspective view of the wheeled hand cart shown in Fig. 1 but in tilted position and showing the back and opposite side, and having the guard rail at the top in raised position.

I claim:

The ornamental design for a wheeled hand cart, substantially as shown.
